FUSE FOR PROJECTILES

Nicolas Emilian Methlin, Paris, France, assignor
to Schneider & Cie., Paris, France, a limited
joint-stock company of France

Application December 13, 1933, Serial No. 702,255
In France April 28, 1933

10 Claims. (Cl. 102—39)

The present invention relates to a delayed arming percussion fuse, constructed in such a manner as to operate by the driving in of one of the elements of the firing mechanism (the striker for example) and by the inertia of the complementary element (the percussion cap carrier), or vice-versa.

The new fuse is characterized in that it comprises, in combination with the front element of the mechanism (the striker) retained by a member withdrawable on impact, such as a pin, a complementary movable rear element, the percussion cap carrier, forming a plunger guided directly in the fuse body and carrying in its front part a segment or other like safety member, which is guided with the plunger over a portion of the path from the rear to the front through which the said plunger travels on operation, but which for arming, is rendered radially withdrawable into a recess in the fuse body. The arming movement of the safety member cannot occur, however, until the plunger has travelled over a suitable fraction of its path, the safety member, during the time it is guided with the plunger, forming an obstacle to the meeting of the striker and the percussion cap.

In a practical constructional form of the invention, the guide between the plunger-like percussion cap carrier and the fuse body, is constructed with a sufficiently small play, or through the medium of a fluid-tight joint, such that the plunger forms a piston and its forward movement is restrained by the impeded passage from the front to the rear thereof of the air or of an appropriate fluid or liquid contained in the chamber closed by the front part of the fuse body.

A practical constructional form of the invention is shown by way of example in the accompanying drawings in which:

40 Figure 1 is a section along the axis of the fuse, the members being shown in the position which they occupy at rest.

Figures 2 and 3 are similar sections showing the members in two successive operative positions.

45 Figure 4 is a similar part section showing the part played by the safety member in the case of premature or accidental rupture of the striker retaining device.

Figure 5 is a section along the line 5—5 of 50 Figure 3.

Figures 6 and 8 relate to a delay-action device combined with the fuse, Figures 6 and 7 being vertical sections showing the members in two different positions, and Figure 8 being a plan section along the line 8—8 of Figure 6.

In these various figures, *a* denotes a fuse body, having an upper element *a*¹ in which is guided a striker *b* retained in the position of rest and up to the moment of impact, for example by a pin *b*¹.

The front element *a* of the fuse body serves directly as a guide for a plunger *c* carrying the percussion cap *d* and resting by its lower face either on a shoulder of the body *a*, or, as shown in the drawings, on a block *e* having an eccentric conduit *e*¹ in which may be placed a delay-action composition *e*². According to the invention, the plunger *c*, directly guided in the body *a*, carries in its front portion a safety member *f*, which moves therewith and is guided in body *a* over a portion of the path through which the percussion cap carrier *c*—*d* travels from the rear towards the front on operation. The guide for member *f* may be constituted by an extension of the guide for the percussion cap carrier. The form of the safety member *f* and the height to which its guide extends are such that the said member, which is radially withdrawable by movement relative to the plunger under the action of the centrifugal force, possibly combined with the action of a spring, prevents, as long as it is guided from the rear to the front, any premature meeting of the striker *b* and the percussion cap *d*, even in the case of premature rupture of the pin *b*¹ (as indicated in Figure 4), or the premature operation 30 of the percussion cap carrier by inertia. In the front portion *a*¹ of the fuse body is a chamber *a*² of greater diameter than that of the guide for the percussion cap carrier and safety member, thereby permitting the safety member *f*, when 35 it has been advanced into said chamber, to be withdrawn under the action of the centrifugal force, possibly assisted by the action of a spring *f*¹ situated between the member *f* and the head of the percussion cap carrier.

The clearance between the plunger *c* and the cylindrical guiding wall of the fuse body element *a* is made sufficiently small, or possibly a packing member such as a cup leather or a metal piston ring is provided, so that the plunger will form a piston and its forward movement will be restrained by the passage towards the rear thereof of the air or any other appropriate fluid confined in the chamber *a*².

The forward movement of the plunger *c* for 50 arming is normally ensured through the medium of a ring *g* guided within the lower recessed portion of and adapted for longitudinal movement relative to the said plunger, and subjected to the action of a spring *g*¹ bearing at its front end 55

against a collar g^2 of the ring, and at its rear end against the block e . If a delay-action block such as e is not combined with the fuse, the rear end of the said spring may bear on a shoulder of the body a , which shoulder would, at the same time, serve as support for the rear face of the plunger.

In the example shown, the ring g is guided in the plunger c and is centered by a collar g^2 on a tubular axial extension e^3 of the block e , the said extension and an axial conduit of the block forming an axial duct e^4 for the transmission of flame from the percussion cap to the detonator h . In a groove g^3 provided in the ring g , are located two elements forming springs g^4 intended to engage a shoulder c^1 of the plunger c and to hold the ring g in the position shown in Figures 2 and 3 after the projectile has been fired.

At rest, the members occupy the position shown in Figure 1, any movement of rotation and any excessive movement of translation of the plunger being prevented by a spring bolt i , the tail of which engages a notch c^2 on the head of the said plunger.

On the departure of the shot from the gun, the ring g lags behind by inertia, thereby compressing the spring g^1 , while the two springs g^4 , as soon as they come opposite the rear large-bore portion c^3 of the plunger below shoulder c can expand to take up a position behind the shoulder c^1 , as shown in Figure 2, and thereafter retain ring g in a fixed position relative to the plunger c . On termination of the initial acceleration due to firing, the spring g^1 expands and carries the ring g forwardly and, through the medium of the springs g^4 , the percussion cap carrying plunger $c-d$. This forward movement is restrained or retarded by the obstruction to the flow of air or other fluid from the chamber a^2 towards the rear of the fuse body offered by the relatively small clearance, or the packing joint provided, between the said plunger and the fuse body a . Premature rupture of the retaining member b^1 , during transport or while the projectile is passing through the bore of the gun, will not be able to bring about the operation of the firing mechanism, due to the fact that the member f is situated on the path between the percussion cap and the striker, and prevents the point of the latter from contacting with the percussion cap until said member has reached its arming position in chamber a^2 . Forward movement of the plunger c is rendered possible by the withdrawal of the bolt i under the action of centrifugal force immediately after the projectile starts to rotate, but the safety member f remains in the path of the striker b as long as the lower base of the said member f has not cleared the shoulder a^3 defining the lower edge of chamber a^2 . During the whole of this time, premature inward movement of the striker, for example under the effect of encountering an obstacle in the vicinity of the muzzle of the gun, will not bring about the operation of the fuse, the striker, as shown in Figure 4, being arrested in its inward movement by the member f .

By suitably predetermining the tension and power of the spring g^1 and the weight of the plunger, and by suitably regulating the air or fluid leakage permitted between the plunger and the fuse body, it is easy to regulate the time which will be required for the safety member f to clear the projection or shoulder a^3 .

When this obstruction to movement has been cleared, the member f is driven outward radially,

under the action of the centrifugal force combined with the action of the spring f^1 . The members are then situated in the position shown in Figures 3 and 5.

In the practical constructional form shown in the drawings, the path of radial outward movement allowed to the member f , is limited by a flange c^4 on the plunger head, which prevents the said member f from being jammed against the wall of chamber a^2 formed in forward portion a^1 of the fuse body and forming a resistance to the operation of the fuse by inertia. When the members are in this position the fuse is armed and may operate by the driving of the striker into the percussion cap when the projectile strikes an obstacle by its point. It may also operate by inertia when the projectile strikes an obstacle by its longitudinal surface, the percussion cap carrier then being driven forwardly with the withdrawn safety device which it carries.

The fuse which has just been described may be combined, as moreover is the case for the constructional example shown, with a delay-action device so adapted that, in addition to the principal function which it fulfills, it combines the function, as shown previously hereinbefore, of serving as a support for the percussion cap carrier c and also as a member for centering and supporting one end of the spring for the ring g for driving the said percussion cap carrier.

The delay-action device in itself may be given various constructional forms. In the example shown in the drawings, it comprises a bolt j which is normally retained in the position which it has to occupy for direct operation (Figures 1, 6 and 8) by a pin k . In this position, the duct j^1 provided in the bolt is opposite the axial duct e^4 of block e and permits the direct transmission of flame between the percussion cap d and the detonator h . If it is desired to cause the fuse to operate with delay after impact, it is merely necessary to drive out the pin k which enables the spring j^2 to move the bolt j radially into a position in which it renders direct communication impossible between the duct e^4 and the detonator h . In this case the flame from the percussion cap d is transmitted to the detonator h by a conduit e^5 in the block e and through the delay composition e^2 .

What is claimed is:—

1. In a delayed arming percussion fuse mechanism for a projectile, a fuse body provided with an axial bore therein, the upper end of said bore being of a larger diameter than the remainder thereof so as to form an enlarged recess in said body, a striker carried by said fuse body with its lower end extending into said recess, means retaining said striker in inoperative position until impact, a percussion cap carrier of plunger-like construction mounted in and in direct sliding contact with the walls of said axial bore, means for positively moving said carrier through said bore to arming position after the projectile has been fired, and a safety member mounted on the upper end of said carrier for axial movement therewith but movable radially with respect thereto, said safety member also having direct sliding contact with the walls of said bore and having a portion preventing contact between the striker and the percussion cap until said member is moved radially outwardly into said recess at the upper end of its axial movement.

2. In a delayed arming percussion fuse mechanism for a projectile, a fuse body provided with an axial bore therein, the upper end of said bore

- being of a larger diameter than the remainder thereof so as to form an enlarged recess in said body, a striker carried by said fuse body with its lower end extending into said recess, means retaining said striker in inoperative position until impact, a percussion cap carrier of plunger-like construction mounted in and in direct sliding contact with the walls of said axial bore, a delay-action device fixed in the lower portion of said axial bore including a block upon which the lower end of said carrier rests when in normal unarmed position, means releasable only after the projectile has been fired for normally maintaining said carrier in said unarmed position, a spring resting upon said block and adapted to positively move said carrier forward through said bore to armed position after the projectile has been fired, and a safety member mounted on the upper end of said carrier for axial movement therewith but movable radially with respect thereto, a spring interposed between said carrier and safety member and tending to move the latter radially outwardly with respect to the former, said safety member also having direct sliding contact with the walls of said bore and having a portion preventing contact between the striker and the percussion cap until said member is moved radially outwardly into said recess at the upper end of its axial movement.
3. In a delayed arming percussion fuse mechanism for a projectile, a fuse body provided with an axial bore therein, the upper end of said bore being of a larger diameter than the remainder thereof so as to form an enlarged recess in said body, a striker carried by said fuse body with its lower end extending into said recess, means retaining said striker in inoperative position until impact, a percussion cap carrier of plunger-like construction mounted in and in direct sliding contact with the walls of said axial bore, means for positively moving said carrier forward through said bore after the projectile has been fired, the clearance between said carrier and the walls of said bore being such that the forward movement of said carrier is retarded by a dashpot action, and a safety member mounted on the upper end of said carrier for axial movement therewith but movable radially with respect thereto, said safety member also having direct sliding contact with the walls of said bore and having a portion preventing contact between the striker and the percussion cap until said member is moved radially outwardly into said recess at the upper end of its axial movement.
4. In a delayed arming percussion fuse mechanism for a projectile, a fuse body provided with an axial bore therein, the upper end of said bore being of a larger diameter than the remainder thereof so as to form an enlarged recess in said body, a striker carried by said fuse body with its lower end extending into said recess, means retaining said striker in inoperative position until impact, a percussion cap carrier of plunger-like construction mounted in and in direct sliding contact with the walls of said axial bore, a safety member mounted on the upper end of said carrier for axial movement therewith but movable radially with respect thereto, said safety member also having direct sliding contact with the walls of said bore and having a portion preventing contact between the striker and the percussion cap until said member is moved radially outwardly into said recess at the upper end of its axial movement, and means for positively limiting the extent of the radial movement of said safety member in said recess so as to prevent contact thereof with the walls of said recess.
5. In a delayed arming percussion fuse mechanism for a projectile, a fuse body provided with an axial bore therein, the upper end of said bore being of a larger diameter than the remainder thereof so as to form an enlarged recess in said body, a striker carried by said fuse body with its lower end extending into said recess, means retaining said striker in inoperative position until impact, a percussion cap carrier of plunger-like construction mounted in and in direct sliding contact with the walls of said axial bore, means for positively moving said carrier forward through said bore after the projectile has been fired, a safety member mounted on the upper end of said carrier for axial movement therewith but movable radially with respect thereto, a spring interposed between said carrier and safety member and tending to move the latter radially outwardly with respect to the former, said safety member also having direct sliding contact with the walls of said bore and having a portion preventing contact between the striker and the percussion cap until said member is moved radially outwardly into said recess at the upper end of its axial movement, and means mounted on said carrier for positively limiting the extent of the radial movement of said safety member in said recess so as to prevent contact thereof with the walls of said recess.
6. In a delayed arming percussion fuse mechanism for a projectile, a fuse body provided with an axial bore therein, a percussion cap carrier of plunger-like construction mounted in and in direct sliding contact with the walls of said bore, said carrier having an axial recess formed therein, means releasable only after the projectile has been fired for normally maintaining said carrier in a rearward unarmed position, and means for moving said carrier forward to armed position after firing comprising an inertia ring mounted within said carrier recess for axial movement relative thereto, a spring interposed between said ring and a fixed portion of the fuse body and exerting a forward thrust against said ring, said spring normally maintaining said ring in a position adjacent the forward end of said carrier recess but yielding to the inertia of said ring when the projectile is fired to permit said ring to move rearward relative to said carrier, and means for locking said ring to said carrier when the ring reaches its rearward position under the influence of the forces exerted at the time of firing, whereupon said spring moves both said ring and carrier forward to armed position.
7. In a delayed arming percussion fuse mechanism for a projectile, a fuse body provided with an axial bore therein, a percussion cap carrier of plunger-like construction mounted in and in direct sliding contact with the walls of said bore, said carrier having an axial recess formed therein, a delay-action device fixed in said axial bore behind said carrier including a block upon which the rear end of said carrier rests when in normal unarmed position, means releasable only after the projectile has been fired for normally maintaining said carrier in said unarmed position, a tubular extension projecting forwardly from said block into said carrier recess, said extension and block having an axial flame transmitting conduit therethrough, and means for moving said carrier forward to armed position after firing comprising an inertia ring mounted within said carrier recess for axial movement relative thereto and guided upon said tubular extension, a spring interposed between said ring and said delay-action device block and exerting a forward thrust

against said ring, said spring normally maintaining said ring in a position adjacent the forward end of said carrier recess but yielding to the inertia of said ring when the projectile is fired to permit said ring to move rearward relative to said carrier, means associated with said tubular extension for determining said forward position of the inertia ring, and means for locking said ring to said carrier when the ring reaches its rearward position under the influence of the forces exerted at the time of firing, whereupon said spring moves both said ring and carrier forward to armed position.

8. In a delayed arming percussion fuse mechanism for a projectile, a fuse body provided with an axial bore therein, the forward end of said bore being of a larger diameter than the remainder thereof so as to form an enlarged recess, a striker carried by said fuse body with its lower end extending into said recess, a percussion cap carrier mounted in said bore for forward axial movement therein to armed position, means releasable only after the projectile has been fired for normally maintaining said carrier in unarmed position, means for moving said carrier forward to armed position after firing comprising an inertia ring mounted for axial movement relative to said carrier, a spring interposed between said ring and a fixed portion of the fuse body and exerting a forward thrust against said ring, said spring normally maintaining said ring in a position adjacent the forward end of said carrier but yielding to the inertia of said ring when the projectile is fired to permit said ring to move rearward relative to said carrier, and means for locking said ring to said carrier when the ring reaches its rearward position under the influence of the forces exerted at the time of firing, whereupon said spring moves both said ring and carrier forward to armed position, and a safety member mounted on the forward end of said carrier for axial movement therewith but movable radially with respect thereto, said safety member having a portion preventing contact between said striker and the percussion cap until the forward end of said carrier reaches the forward portion of said bore and said safety member is moved radially outwardly into said recess.

9. In a fuse mechanism for projectiles wherein a percussion cap is moved axially forwardly with respect to the fuse body into position for firing contact with a striker, the combination of a carrier for said percussion cap slidably mounted within said fuse body, an inertia member mounted for axial movement relatively to said carrier, a spring interposed between said inertia member and a portion of the fuse body, said inertia member normally occupying a position forward with respect to said carrier but movable rearwardly with respect thereto upon firing of the projectile from the gun, thereby compressing the spring, means for locking said inertia member to said carrier in its rearward position, and means independent of said inertia member for normally locking said carrier to said fuse body in unarmed position, said last-named locking means being automatically releasable after the projectile is in flight so as to permit the force of the compressed spring to be transmitted to said carrier and to move the latter axially forwardly toward the striker.

10. In a fuse mechanism for projectiles wherein a percussion cap is moved axially forwardly with respect to the fuse body into position for firing contact with a striker, the combination of a carrier for said percussion cap slidably mounted within said fuse body, an inertia member mounted for axial movement relatively to said carrier, a spring interposed between said inertia member and a portion of the fuse body, said inertia member normally occupying a position forward with respect to said carrier but movable rearwardly with respect thereto upon firing of the projectile from the gun, thereby compressing the spring, means for locking said inertia member to said carrier in its rearward position, and a locking bolt mounted in said fuse body and extending radially inwardly thereof to engage said carrier when the latter is in its at rest position, said locking bolt being automatically withdrawn under the action of centrifugal force after the projectile is in flight so as to permit the force of the compressed spring to be transmitted to said carrier and to move the latter axially forwardly toward the striker.

NICOLAS EMILIEN METHLIN.
